UNITED STATES PATENT OFFICE

LEE E. MORRISON, OF PORTLAND, OREGON

REFRIGERATOR CABINET

Application filed May 11, 1931. Serial No. 532,424.

My invention relates to refrigerator cabinets adapted for domestic use in which thick walls of insulating material form a chamber to contain the refrigerating element and food stores, and more particularly to means for enhancing the utility and capacity thereof.

The principal object of my invention is to provide quick and convenient access to every part of the storage places.

10 A second object of my invention is to effect an economy of space required for a cabinet of a given capacity.

A third and incidental object is to effect certain economies in refrigeration.

15 Other objects and advantages of my invention will be apparent in the following discourse wherein the significance of the reference characters in the accompanying drawing, details of construction of a typical cabinet embodying my invention, and the particular advantages thereof are explained.

20 Figure 1 represents a view of a section in a horizontal plane of the entire cabinet showing the relationship of the several parts characterizing my invention.

Figure 2 represents a view of a section in a vertical plane of a lower fragment of the cabinet showing in lateral aspect certain of the characteristic devices illustrated in Figure 1.

25 Figure 3 represents a front view of typical parts of the mechanism shown in Figure 1.

Figure 4 represents a front view of the entire cabinet illustrative of the unique manner in which the door thereof is hinged.

30 My invention consists in the particular combination of the manner in which the door is hinged, the extensibility of drawers forming an essential part thereof of approximately the same width as the refrigerating chamber when the door is opened through ninety degrees, and the special means affording easy operation of the said drawers in which only the friction of pivotal joints is involved as opposed to that involved in parts relatively 35 slideable.

Two pairs of vertically pivoted links of symmetrical design, indicated by the numerals 1 and 2 and 3 and 4 respectively, are pivotally attached to the cabinet-lining at the in-

ner corners thereof 5 and 6 respectively, and to the corners of the drawer 15 at 7 and 8 respectively, constitute the means for supporting the drawers in any position between the limits of motion thereof.

To guide the drawer in true rectilinear motion recourse is had to means for constraining the similar links of both pairs to angular motion of equal magnitude with respect to the rear wall of the cabinet and the 40 rearmost surface of the drawer respectively, incidentally providing for the parallel relationship of this rearmost surface of the drawer and the rear wall of the cabinet at all positions of the drawer.

45 The particular means found convenient to effect this equi-angular movement of the several links comprises these parts:

At the rear of the cabinet, two rods 9 and 10 are pivotally attached to the links 2 and 4 respectively, at some equal distance from the pivotal attachment of the latter to the cabinet corners. The other ends of these rods 9 and 10 are connected to the ends of equal arms of the centrally pivoted lever 11, illustrated in 50 detail in Figure 3.

Similar mechanism comprising the parts 12, 13, and 14, respectively, govern the movement of the links 1 and 3 in equi-angular movement with respect to the rearmost surface of the drawer.

55 The door 16 is hinged to the cabinet so that it will swing about an axis 17 situated approximately as far removed from the cabinet opening as the door is thick. Since, it is sound practice to provide equal thermal insulation in the cabinet walls and the door, the hinging of the door in this wise fixes the position of the hinge-pin at the extreme corner of the cabinet. This is in distinct contrast to the ordinary practice of hinging the door adjacent the cabinet opening which method of hanging the door necessitates the swinging thereof through an angular distance of 180 degrees, or thereabouts, to effect 60 the full opening of the cabinet to allow of withdrawing the drawers.

65 In Figure 1 a line A indicates the surfaces of two room-walls forming a corner in which it is advantageous to place a refrigerator in 70

view of the degree of protection such a location in a room provides against warm drafts. Thus located, the full utility of the refrigerator of my invention is in no wise impaired.

5 A refrigerator of the ordinary type placed in such a position would be difficult of access owing to the impossibility of opening the cabinet to its full width by a movement of the door through a right angle.

10 While it is acknowledged that a refrigerator of the ordinary type may be protected from warm drafts by placing it in a specially constructed room with a refrigerator niche, it will be obvious that the cabinet of my invention will be of more general utility in its universal adaptability to any room of the common place design in which the cabinet may be located to advantage in any of the four or more corners.

15 20 Aside from these considerations, the times required for opening and closing the door of a given weight, which contemplates the accelerations and retardations of the given mass of the door, through 180 degrees of angular movement on the one hand and through 90 degrees on the other hand, are in distinct contrast.

The drawer supporting and extending device of my invention with its comparatively 30 free and easy motion further economizes the time the door must be held open to accomplish any act of removing or depositing stores. A bowl of liquid to be chilled may be set upon the extended drawer and the same returned 35 to its inner position quickly without danger of spilling such liquid,—an advantage accruing out of the easy movement of the drawer.

40 Specifically, in refrigerator cabinets, exposed surfaces are liable to becoming incrusted with various foreign matter and working surfaces, such as are inherent in the ordinary drawer slides, sooner or later become fouled and prevent the easy motion 45 of a drawer desired. In distinction to this, the device of my invention provides for the constant engagement of all working surfaces and hence the protection thereof against such incrustation.

50 Further, specifically, any liquids which may congeal about the working parts of the device of my invention, are subjected to a relatively great force to disintegrate the same upon the withdrawal of a drawer owing to the 55 leverages involved as contrasted with an ordinary drawer slide where such congealed liquids obstructing the free movement of the drawer are of greater extent and in simple stress to resist movements of the drawer in 60 easy uniform movement.

65 It will thus be obvious that the particular manner of hanging the door in combination with the drawer supporting device contribute in a very definite and desirable degree to the thermal efficiency of the refrigerator cabinet

besides providing for an enhanced facility of removing and depositing stores.

Having described my invention, what I claim is:

1. A cabinet, a drawer of substantially the same width as the chamber in said cabinet normally housed therein, and a device extensibly supporting said drawer in said cabinet comprising, two pairs of pivotally joined links extremities of which pairs are pivotally attached to inner corners of said cabinet and said drawer respectively and means for constraining the links attached to said drawer and the links attached to said inner cabinet corners to equi-angular motion respectively. 70 75 80

2. A cabinet, a drawer of substantially the same width as the chamber in said cabinet normally housed therein, and a device extensibly supporting said drawer in said cabinet comprising, two pairs of pivotally joined links extremities of which pairs are pivotally attached to inner corners of said cabinet and said drawer respectively and two levers pivotally attached to said drawer and the rear inner wall of said cabinet respectively equal arms of each thereof being pivotally connected by suitable rods to each of said links respectively to constrain the links attached to said drawer and the links attached to said inner cabinet corners to equi-angular motion respectively. 85 90 95

3. A cabinet comprising, an open chamber, a door of the same thickness as the walls of said chamber forming a closure therefor, hinges attaching said door to a wall of said chamber in which the axes thereof are disposed in a plane which bisects the angle included between the inner adjacent sides of said chamber wall and said door when the latter is in the closed position, a drawer of substantially the same width as the chamber in said cabinet normally housed therein, and a device extensibly supporting said drawer in said cabinet comprising, two pairs of pivotally joined links extremities of which pairs are pivotally attached to inner corners of said cabinet and said drawer respectively and means for constraining the links attached to said drawer and the links attached to the said inner cabinet corners to equi-angular motion respectively. 100 105 110 115

4. A cabinet comprising, an open chamber, a door of the same thickness as the walls of the said chamber forming a closure therefor, hinges attaching said door to a wall of said chamber in which the axes thereof are disposed in a plane which bisects the angle included between the inner adjacent sides of said chamber wall and said door when the latter is in the closed position, a drawer of substantially the same width as the chamber in said cabinet normally housed therein, and a device extensibly supporting said drawer in said cabinet comprising, two pairs of pivotally attached to inner corners of said cabinet and said drawer respectively and means for constraining the links attached to said drawer and the links attached to the said inner cabinet corners to equi-angular motion respectively. 120 125 130

totally joined links extremities of which pairs are pivotally attached to inner corners of said cabinet and said drawer respectively and two levers pivotally attached to said drawer and to the rear inner wall of said chamber respectively equal arms of each thereof being pivotally connected by suitable rods to each of said links respectively to constrain the links attached to said drawer and the links attached to said inner chamber corners to equi-angular motion respectively.
